UNITED STATES PATENT OFFICE.

HERMAN W. PETH, OF ROCHESTER, NEW YORK.

PRESSING-IRON.

1,395,355.

Specification of Letters Patent.

Patented Nov. 1, 1921.

Application filed August 21, 1918. Serial No. 250,877.

To all whom it may concern:

Be it known that I, HERMAN W. PETH, a citizen of the United States, and resident of Rochester, in the county of Monroe and 5 State of New York, have invented certain new and useful Improvements in Pressing-Irons, of which the following is a specification.

The present invention relates to pressing 10 irons and more particularly to the type in which a steam chamber is provided within the iron body for heating the iron, and a plurality of steam escape openings is provided in the bottom of the iron for the purpose of moistening the surface to be pressed, 15 suitable means being employed for controlling the escape of steam through the openings from the steam chamber.

An object of this invention is to provide 20 an inexpensive construction in which the controlling means is simple in operation and not liable to get out of order and the operating parts are subject to ready repair.

To these and other ends the invention 25 consists of certain parts and combinations of parts, all of which will be hereinafter described, the novel features being pointed out in the appended claims.

In the drawings:—

30 Figure 1 is a vertical section through an iron constructed in accordance with this invention;

Fig. 2 is a detail view of the valve operating devices;

35 Fig. 3 is a detail view of the valve; and Fig. 4 is a vertical section on the line 4—4, Fig. 1.

The present application discloses certain features which are also found in an application filed by me on June 13, 1917, and to 40 these features the present application is a division of said application.

In the illustrated embodiment of the invention, 1 indicates the iron body formed 45 from a single casting with a steam chamber 2 into which steam is delivered by an inlet 3. The latter in this instance is in the form of a pipe extending from the rear wall of the body to a point near the front end of the 50 body and situated in spaced relation to the bottom of the chamber. An outlet for the steam is provided in the rear wall and is situated at a point slightly below the bottom of the chamber so that water of condensation 55 may readily pass from the steam chamber.

An additional chamber 5 is provided with

in the iron body, this chamber preferably being elongated and extending nearly the full length of the chamber 2, its ends being deflected upwardly at 6 and through the top 60 of the iron where such ends are closed by plugs 7. The purpose of forming the chamber 5 with upwardly-extending ends is to permit the formation of said chamber in the casting operation. The chamber 5 has its 65 upper wall above the bottom wall of the chamber 2, and its lower wall below the bottom wall of the chamber. Fins or lugs 8 may be projected from the top wall of the chamber 5 into the chamber 2 and the bottom 70 wall of the chamber 2 may likewise have such upwardly-projecting fins for the purpose of conducting heat to the bottom of the iron. From the chamber 5 a plurality of perforations or openings 9 extend through 75 the bottom wall of the iron body, in order to permit steam to pass from the chamber 5 through the bottom face of the iron for the purpose of moistening the goods which are to be pressed. These openings are prefer- 80 ably comparatively small and the series extends in a line longitudinally of the iron.

Steam is admitted into the chamber 5 from the chamber 2 by a port or opening 10, which, in this instance, is formed eccentrically within a plug 11 fitted by screw threads thereon in a larger opening in the top of the chamber 5. This plug 10 may also have a central depression 12 in which one end of the valve stem 13 is fitted, said stem carrying, in this instance, a valve disk 14 co-operating with the plug 11 and provided with an eccentrically arranged opening 15 which may be brought into register with the opening 10 in order to provide communication 90 between the chamber 2 and the chamber 5. About the rotary plug 14 the plug may be provided with an upwardly-extending flange 16 which serves to center the valve 14 when the latter is being fitted to its seat on the 95 plug 11, this flange having openings 17 through which water of condensation may be passed so that the water will not collect about the valve 14. The opening 10 being situated in the top wall of the chamber 5 and above the bottom wall of the chamber 2, there is no tendency for any water of condensation to pass through the chamber 2 to the chamber 5.

The iron is manipulated by a handle 18 110 which is held by a nut 19 on the upper tapered end of a handle stem 20. This

handle stem has a removable steam-tight connection with the iron body 1, and to this end the lower end of the stem is provided with a screw-threaded portion 21 and a surrounding shoulder or abutment 22, the screw-threaded portion engaging within an internally-threaded bore 23 in the top wall of the iron body 1 directly over the valve 14 and the plug 11, so that the valve and plug may be introduced through the opening 28. It is preferred to mount the valve 14 on the handle, and to this end the stem 20 has a central bore 24 through which the valve stem 13 extends to project beyond the lower end of the handle stem 30 and to carry the valve 14 on its projecting end. Between the valve 14 and the lower end of the handle stem 20 a helical spring 25 may be arranged in order to maintain the valve 14 yieldingly against the seat on the top of the plug 11. The upper end of the valve stem 13 extends through a stuffing box 26 at the upper end of the handle stem 20 and is provided with a laterally operating arm 27. This lateral operating arm is preferably held in position to close the valve 14, and to this end there is employed a spring 28 coiled about the projection 29 on the handle 18 and having an arm 30 bearing against a depending projection 31 on the valve stem arm 27. This spring arm 30 permits the handle-operating arm to be turned to a position where the opening 15 in the valve 14 may be brought into register with the opening 10 in the plug 11, so that communication may be established between the chamber 2 and the chamber 5. The iron as a whole may be supported by a bearing member 34^a from a pressing machine of any suitable type, said bearing member surrounding the stem 20 and to this end having a portion 33 formed with an opening 32. The portion 33 has a rocking bearing between two bearing blocks 34 held between the shoulder 22 and the lowermost portion of the handle 18.

In the use of the invention the steam supply is connected to the steam inlet 3 to supply steam to the chamber 2, the exhaust of said steam taking place by way of the outlet 4. This effects the heating of the iron body to a temperature sufficient to produce a pressing action without any danger of burning or scorching the goods. Should it be desired to moisten the goods, the handle 27 is manipulated by the thumb of the user, and this effects the turning of the valve 13 to bring the opening 15 in the valve into registration with the port 10 in the plug 11, thus admitting steam to the chamber 5 from which it exhausts through the openings or perforations 9 in the bottom or ironing face of the iron.

An iron constructed in accordance with this invention is very effective for pressing goods without scorching or burning. The

goods may be moistened without sponging which tends to produce spots. The valve arrangement by which steam is conducted from the steam heating chamber to the steam exhausting chamber is of simple construction and not liable to get out of order, the valve being effectively held to its seat by a yielding pressure while being readily movable to provide communication between the chambers. The opening between the chambers is formed in the top wall of the steam exhausting chamber above the bottom of the steam heating chamber and, as a consequence, there is no danger of water of condensation passing into the steam exhausting chamber. This communication is situated directly below an opening in the top of the iron body in which the handle is secured. The valve is mounted on the handle so as to be removable therewith, the spring which holds the valve to its seat having an abutment on the handle stem and removable with the handle and the valve.

What I claim as my invention and desire to secure by Letters Patent is:—

1. A pressing iron having a steam chamber into which the steam is delivered for heating the iron, said chamber having an opening in its top wall, a second chamber having an opening situated directly below the opening in the top wall of the first-named chamber, through which steam is received from said first-named chamber, and also having openings leading through the bottom wall of the iron to discharge steam on the material to be pressed, a handle having a hollow stem formed with a screw threaded portion removably secured in the opening of the top wall, a valve for controlling the opening between the chambers, a valve stem to which the valve is secured, extending through the hollow stem of the handle and removable with the latter and the valve through the opening in the top wall and a packing gland for the valve stem arranged on the hollow stem of the handle.

2. A pressing iron having a steam chamber into which the steam is delivered for heating the iron, a second chamber having an opening through which steam is received from said first-named chamber, and also having openings leading through the bottom wall of the iron to discharge steam on the material to be pressed, a handle having a hollow stem removably secured to the iron body, a valve for controlling the opening between the chambers, having a stem extending through the hollow stem of the handle and removable with the handle, and a spring for holding the valve to its seat arranged about the valve stem below the lower end of the handle stem within the steam heating chamber and abutting said hollow handle stem.

3. A pressing iron having a steam cham-

- ber into which the steam is delivered for heating the iron, said chamber having an opening in its top wall, a second chamber having an opening situated directly below the opening in the top wall of the first- 30
5 the opening in the top wall of the first-named chamber, through which steam is received from said first-named chamber, and also having openings leading through the bottom wall of the iron to discharge steam on the material to be pressed, a plug of a size to be pressed through the opening in the top wall fitted 35
10 on the material to be pressed, a handle having a hollow stem with a threaded lower portion fitted in the opening in the top wall of the first-named chamber, a valve for controlling the opening between the chambers 40
15 having a diameter less than the opening in the top wall of the first named chamber so as to be passed through said opening, a valve stem for the valve extending through the hollow stem of the handle and removable 45
20 with the latter, and a spring surrounding the valve stem to hold the valve to its seat, said spring lying in the steam chamber and abutting the lower end of the hollow handle stem.
25 4. A pressing iron having a steam chamber into which the steam is delivered for
- heating the iron, said chamber having an opening in its top wall, a second chamber having an opening situated directly below the opening in the top wall of the first- 30
5 the opening in the top wall of the first-named chamber, and also having openings leading through the bottom wall of the iron to discharge steam on the material to be pressed, a plug of a size to be pressed through the opening in the top wall fitted 35
10 in the opening in the top wall of the second chamber and provided with an opening and a valve seat, a rotary valve coöperating with said valve seat to control the opening in the plug, a handle having a hollow stem removably connected to the iron, a valve stem rotatable in said hollow handle stem and projecting from both ends of said stem, its lower end projecting into and having bearing in said plug, the valve being mounted on the lower projecting end, a spring arranged between the valve and the lower end of the hollow stem about the valve stem, and an operating handle on the upper end of the valve stem.

HERMAN W. PETH.
